UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 17,917, dated November 29, 1887.

Application filed October 15, 1887. Serial No. 252,488. Term of patent 3½ years.

To all whom it may concern:

Be it known that I, JENNIE SHEILS, of the city, county, and State of New York, have invented and produced a new and original Design for a Pattern of a Lady's Costume; and I do hereby declare that the engraved prints accompanying this specification convey to any one accustomed to using paper patterns a clear understanding of how a garment made up by the pattern will appear.

The design shows a basque and a round walking-skirt. The skirt exhibits a short upper left-side drapery that displays a looping at the center and plaits at the belt and falls over a side-plaited drapery which extends nearly to the edge of the skirt at its front edge and is short at its back edge; a deep full front drapery that extends from the left-side draperies across to the right-side back seam, and exhibits deep forward-turning plaits at the top and loopings at the right side, where it falls much shorter than at the front edge; a lower back drapery that displays kilt-plaits at its center and falls even with the edge of the skirt, and a full upper back drapery that separates at the center, falls over the sides of the lower drapery to the lower edge, and exhibits a deep downward-turning loop in each front edge near the top and draping plaits at the center near the top. The basque displays close-fitting fronts that exhibit a closing down the center and a lapel ornament down either side of the closing, the ornament displaying cascade folds above the bust, and shaping a point at the lower end of the closing, a close-fitting back, a standing collar, and coat-sleeves. The outline of the basque shapes a point at the center of the back and at the closing and a high arch at the sides.

What I claim as my invention, and desire to secure by Letters Patent, is—

The design for a lady's costume, as shown in the engraved prints accompanying this specification.
